UNITED STATES PATENT OFFICE.

SARKIS JELALIAN, OF PROVIDENCE, RHODE ISLAND.

DIRIGIBLE AIRSHIP.

1,108,444.

Specification of Letters Patent. Patented Aug. 26, 1914.

Application filed December 10, 1912. Serial No. 736,028.

To all whom it may concern:

Be it known that I, SARKIS JELALIAN, a citizen of the United States, and resident of the city and county of Providence and State of Rhode Island, have invented certain new and useful Improvements in Dirigible Airships; and I do hereby declare the following specification, taken in connection with the accompanying drawings, forming a part of the same, to be a full, clear, and exact description thereof.

The invention relates to dirigible air-ships, and more particularly to that class of air-ships employing a dirigible balloon for assisting in lifting and sustaining the ship and embodying rotary wings and propellers for driving a ship forward.

The object of the invention is to generally improve this class of air-ship, and it consists in certain novel and peculiar features of construction and combination of parts, as hereinafter described and claimed.

In describing the invention in detail, reference will be had to the accompanying drawings, in which—

Figure 1 is a side elevation of my novel form of air-ship. Fig. 2 is a top-plan view of the car or hull of the ship. Fig. 3 is a side view of the car or hull of the ship. Fig. 4 is a top-plan view of the forward end of the car or hull of the ship. Fig. 5 is a side elevation of the balloon or gas-bag of the ship. Fig. 6 is a bottom-plan view of the frame which supports the balloon or gas-bag.

Referring to the drawings, 1 designates a car or hull of the completed air-ship, which may be of any suitable configuration and construction. Said car 1 is provided upon the bottom with runners 2 for supporting the car when resting upon the ground or when landing, and with openings or windows 3 in both sides of the car and an opening 4 in the bottom thereof, for observation purposes. Said opening 4 is also utilized to suspend a weight from the car to steady the same when moving through an unusually heavy wind. Extending from the stern of the car 1 is a customary form of rudder 5, and mounted upon the bow is a revolving propeller 6, which constitutes one of the means for driving the car forward. Said propeller 6 is mounted upon one end of a shaft 7, upon the other end of which is a beveled pinion 8 which meshes with a pinion 9 upon shaft 10. Also mounted upon the

shaft 10 is a sprocket-wheel 11, adapted to be driven by a sprocket-chain 12, running over a second sprocket-wheel 13 mounted upon a shaft 14, extending transversely across the shaft and beyond the sides thereof, said shaft being provided at each end with a revolving wing or propeller 15, all as shown in Fig. 2. Mounted upon said shaft 14 is a second sprocket-wheel 16, which is driven by a sprocket-chain 17 from a sprocket-wheel 18, mounted upon a main shaft 19 extending transversely across the car adjacent to the central portion thereof. Mounted upon the main shaft 19 is a second sprocket-wheel 20, which cooperates with a sprocket-chain 21 to drive a second sprocket-wheel 22, secured upon a transverse shaft 23, extending beyond each side of the car and provided upon each outer end with a revolving wing or propeller 24, which are duplicates of the propellers 15. The main shaft 19 may be driven by any type of power-generating device, such as a gasolene engine. Extending transversely across the central portion of the car 1 and beyond the sides thereof is a shaft 25, which is provided at each outer end with a bird-like wing 26, which is given reciprocating or flapping motion by means of a toggle connection 27 secured upon said shaft 25 and the main shaft 19, as shown in Figs. 2 and 3.

Extending transversely across the ship between the shafts 14 and 25 is a platform 28, and extending through the platform is a vertical shaft 29 carrying a steering-wheel 30 at the free end thereof, and secured upon said shaft 29 above the platform 28 and extending forward, between the bow of the ship is a second rudder or steering blade 31, as shown in Figs. 3 and 4. Extending around the top of the car 1 is a series of supports or stanchions 32, which support a dirigible or balloon frame 33, upon which is secured the turtle-shaped balloon 34. The frame 33 has a central elongated opening 35, which is preferably covered with canvas 36 to give additional buoyancy to said frame, and with a lateral projection or outrigger 37 extending from the bow upon either side to a point adjacent the stern and with a rearwardly extending tail-portion 38, as shown in Figs. 5 and 6. These lateral projections 37 and 38 serve not only to increase the buoyancy of the air-ship after it has risen, but also serve as a support for the balloon 34 in case the same collapses, and they are held in po-

sition by means of a series of wire supports 39, as shown in Fig. 1.

Fastened to the bow of the ship at the top of the car 1 is a rope 40, which extends 5 through a pulley 41 upon the transverse beam 42, directly above the steering-wheel 30, and the free end of said rope is arranged in close proximity to said steering-wheel so as to be operated by the steersman. 10 Extending from the stern of the ship is a second rope 43, which extends through a pulley 44 upon the beam 42, and the free end of this rope is likewise arranged in close proximity to the steering-wheel 30. 15 The purpose of the ropes 40 and 43 is to provide means for raising either the bow or the stern of the ship as desired by the steersman.

The operation of the device will be readily understood, and it will be seen that by reason of the four revolving wings 15 and 24 and the reciprocating wings 26 upon the sides of the ship, in addition to the usual propeller 6 at the bow, the ship has an unusual amount of driving power when all of the wings and propellers are in operation. It will also be seen that these wings also tend to give the ship additional buoyancy, as they are located directly beneath the lateral projections 37 and when operating force the air up against said outstretched lateral projections.

It will be understood that I do not wish to limit myself to the exact shape and construction of the various novel parts of my improved air-ship and that certain changes may be made in said parts without diverging from the spirit or scope of my invention.

What I claim as my invention and desire 40 to secure by Letters Patent is:

1. An apparatus of the character described comprising a car, a flat frame mounted above said car, a lateral projection extending from the bow and each side 45 of said frame, a revolving propeller at the forward end of said car, revolving propellers and a vertically reciprocating wing upon each side of the car, all of said propellers and wings being located directly beneath said lateral projection, means for operating said propellers and wings, and a gas bag supported upon said frame.

2. An apparatus of the character described comprising a car, a flat frame 55 mounted above said car and provided with an elongated central opening covered with

canvas, a lateral flange extending from the bow and each side of said frame, a flat flaring tail portion extending from said frame, and a gas-bag mounted upon said frame and 60 having a flat bottom and an oval top.

3. An apparatus of the character described comprising a car, propellers carried by said car, means for driving said propellers, a flat-frame mounted above said 65 car upon a series of vertical supports and provided with an elongated central opening, a lateral flange extending from the bow and each side of said frame, a tail portion extending from said frame, and a turtle-shaped gas-bag supported by said frame.

4. An apparatus of the character described, comprising a car, a vertical stationary shaft within and near the front part 75 of said car, a tubular shaft loosely mounted on the said first mentioned shaft and having a hand wheel secured at its upper end, a flat vertical rudder having its rear edge secured to the said tubular shaft and its front edge provided with a lower cutaway portion, a segmental member secured to the car and designed to form a support for the cutaway portion of the rudder, and a locking means to hold the latter in various angular positions upon the said supporting member. 80

5. An apparatus of the character described, comprising a car having a surrounding wall, a flat frame closing the bottom of said car and secured to the wall of the latter, said frame composed of a layer 90 of fine wire gauze and a canvas cover secured beneath the same, to lessen the downward movement of the apparatus, a sliding door arranged in the said frame, and tread members each of a scalloped form secured to the side walls of the car.

6. An apparatus of the character described, comprising a gas bag having a flat closed bottom to form a frame, said frame composed of a layer of fine wire gauze and 100 a canvas cover secured beneath the latter, said frame so constructed to lessen the falling movement of the apparatus whenever the bag should collapse, a laterally projecting flange extending from the front end and 105 sides of said frame, and a flat outwardly-extending tail portion projecting from the rear end of said frame.

SARKIS JELALIAN.
